UNITED STATES PATENT OFFICE.

CLARENCE E. EDGERLY, OF BIDDEFORD, MAINE.

GAME APPARATUS.

SPECIFICATION forming part of Letters Patent No. 709,144, dated September 16, 1902.

Application filed August 28, 1901. Serial No. 73,609. (No model.)

To all whom it may concern:

Be it known that I, CLARENCE E. EDGERLY, a citizen of the United States, residing at Biddeford, in the county of York and State of 5 Maine, have invented a new and useful Game Apparatus, of which the following is a specification.

This invention relates to game apparatus, which may be termed "parlor polo," and the 10 purpose of the same is to provide a simple form of amusement or pastime designed to accurately train the eyes of the players in relation to distances and angles of movement by the aid of a playing-piece and impelling 15 devices therefor on a playing-field of particular arrangement having opposite goals.

The invention consists in the construction and arrangement of the several parts, which will be more fully hereinafter described and 20 claimed.

In the drawings, Figure 1 is a perspective view of a game apparatus embodying the features of the invention. Fig. 2 is an enlarged longitudinal vertical section of the same 25 broken away. Fig. 3 is a transverse vertical section of a portion of the apparatus on an enlarged scale.

Similar numerals of reference are employed to indicate corresponding parts in the several 30 views.

The numeral 1 designates a box or closure having a bottom 2, which constitutes the playing-field and surrounded by upstanding sides 3 and ends 4 of a suitable height. The dimensions of these parts may be regulated at 35 will, and the materials employed in constructing the same will be those best adapted for the purpose. Surrounding the inner portions of the sides and ends and bearing upon the latter and the bottom 2 are cushion-strips 5, which are formed with undercut outwardly-inclined recesses 6, as clearly shown in Fig. 3, to receive a rubber cushion 7, suitably secured in said recesses and continuing regularly and 40 unbrokenly around the field except at points which will be hereinafter set forth. At the center of each end 4 close to the bottom 2 goal-openings 8 are formed through the strips 5 and the said ends, and over the exterior portions of the said openings flexible pockets 9, of suitable material, are applied. The upper 45 plane of the bottom 2 is coincident with the

lower portions of the openings 8, and secured to the said bottom 2 across the entrances to said openings are guard-rails 10, which preferably 50 have inner curved faces intersecting outer vertical edges to prevent the playing-piece passing into the openings from returning to the playing-field. At a suitable distance above the playing-field and extending over the inner 55 portions of the goal-openings are curved wire guards 11, against which the player shielding his goal holds the impelling device employed for moving the playing-piece to prevent an opposing player, if possible, from driving the 60 playing-piece into the goal so protected and also to prevent a player from entirely excluding entrance to his goal or placing the impelling instrument close to the inlet of the opening of the goal. The playing-field is divided 65 into three parts 12, 13, and 14, the parts 12 and 13 being the exclusive territory of the players adjacent thereto and the part 14 neutral territory intermediate of the parts 12 and 13, where either player may endeavor to 70 impel or shoot the playing-piece and which will be regulated by quickness of movement and general dexterity of the players. The field is so divided by a cord, wire, or other device 15 of a similar nature, which is secured at one end in one of the sides 3, as 75 shown by Fig. 1, and then carried across to the opposite side 3 in a straight line and threaded through openings 16 in said last-mentioned side and again brought back to the 80 first-mentioned side and threaded through an opening 17, and from said opening the terminal of the cord or the like is caused to engage a winding-key 18 below the plane of the opening 17, the said key being operated to 85 keep the cord or the like in taut condition. The cord 15 or the like is located at a suitable elevation above the upper plane of the bottom 2, and when arranged as set forth it provides a rectangular inclosure forming the 90 part 14. As shown by dotted lines in Fig. 1, the impelling devices each comprise a shaft or shank 19, with a lower curved extremity 20 for engaging an impelling spherical playing-piece 21, preferably in the form of a steel 95 ball.

The game is played by two persons, situated at the ends 4 and each provided with one of the impelling devices. The object of

the game is for the opposing players to drive the ball 21 into the goals, and by a suitable arrangement said goals when successfully made will count a certain number of points.

5 To start the game, the ball 21 is placed in the central part 14 of the playing-field and each player then proceeds to get control of the ball. Neither player is permitted to put his impelling device over the cord 15 or the like, but 10 each player can reach as far as his impelling device will permit him to do from his side under the portion of the cord nearest to him, and when one of the players succeeds in obtaining control of the ball he immediately places 15 it in the best possible position for a drive toward the goal of his opponent, and the said opponent places his impelling device against the guard-wire 11 to shield as much as possible his goal and endeavor to prevent entrance of the ball thereinto. The players are 20 not permitted to arrange the extremities of the impelling devices within the wire guards so as to give an opponent a chance to make the guarded goal by an accuracy in movement of the ball with this end in view. When 25 the impelling devices are held straight against the guard-wires, they will prevent the ball being driven into the goals in straight lines, but by a suitable angular movement the ball may be caused to strike the cushion 7 on 30 either side in such manner as to carom into the goal desired to be made. It is also obvious that the sideshot is the best to be made in view of the fact that if the goal is missed 35 the ball will return, in all probability, back to the territory or part of the board or field from which it was impelled, and thereby permitting the players to have successive shots. If the ball stops within the territory of either 40 player or in either of the parts 12 or 13, the player having control of the part 13 is not permitted to touch the ball when it is in the part 12, and vice versa. When the ball is driven toward the goal by one of the players, 45 the player so guarding his goal is at liberty to move his impelling-piece around the guard-wire 11 to ward off the ball, and by practice players will become very adept in shielding their goals in a legitimate manner, and thus 50 render it very difficult for the opposing player to effect an entrance to a guarded goal. It is proposed to have ten points constitute a game, and if the ball is knocked out of the box it is called a "foul," and two fouls will 55 take off one point in the game. When the ball is driven into either one of the openings 8 and passes into the adjacent pocket 9, it can be readily put into play again by the player nearest the pocket lifting the latter and causing 60 the ball to pass in reverse direction onto

the playing-field through the adjacent opening 8. The impelling devices should be held between the first two fingers and thumb, with the upper end of the same in the palm of the hand. Many complex shots can be devised by the use of the cushion, and the rebound of the latter may be utilized for formulating combination-shots, and with practice the eye of the player will become accurately trained as to the certainty of various angle contacts to arrive at the result sought.

In constructing or joining the several parts of the apparatus those methods will be used by which strength may be derived as well as economy in the use of material, and while the preferred form of the apparatus has been shown and described it will be understood that changes in the form, size, proportions, and minor details may be resorted to without departing from the principle of the invention.

Having thus described the invention, what is claimed as new is—

1. A game apparatus comprising an inclosure having a pocket for the reception of a playing-piece, and a curved wire guard arranged in front of and at a distance from the mouth of the pocket and in a plane above that of the playing-piece.

2. A game apparatus comprising an inclosure having a bottom playing-field surrounded by a yielding cushion and provided with a goal or pocket at each end for the reception of a playing-piece, and a guard disposed in front of and at a distance from the mouth of each goal, said guards being arranged in a plane above that of the playing-piece.

3. A game apparatus comprising an inclosure having goals or pockets for the reception of a playing-piece, and inwardly-projecting curved guards, arranged at a distance from the mouth of each goal thereby to prevent the closing of the mouth of the goal by the impelling device.

4. A game apparatus comprising in combination, an inclosure having a goal or pocket for the reception of a playing-piece, a curved guard disposed in front of the mouth of the pocket in a plane above that of the playing-piece, and an impelling device adapted to engage in front of said guard, said impelling device being of a width less than that of the goal or pocket.

In testimony that I claim the foregoing as my own I have hereto affixed my signature in the presence of two witnesses.

CLARENCE E. EDGERLY.
